COUCH

Herbert A. Wuest, Cincinnati, Ohio, assignor to
 Adam Wuest, Inc., Cincinnati, Ohio, a corporation of Ohio

Application April 5, 1937, Serial No. 134,948

5 Claims. (Cl. 5—44)

This invention relates to couches of the character generally referred to as studio couches. The invention is concerned with means for extending one portion of the device relative to another portion thereof whereby a double bed may be provided.

An object of the invention is to provide a simple and efficient arrangement of parts for providing an extensible arrangement of bed forming parts 10 of such a device.

Another object is to provide an arrangement of parts that will permit ready separation of the relatively extensible parts whereby to provide, if desired, a plurality of separate bed portions, in 15 the nature of twin beds.

Another object of the invention is to obviate certain objectionable features present in prior art devices of the character referred to as sofas, and wherein there are likewise relatively movable 20 parts for providing an extended bed.

Another object is to provide an arrangement of parts for accomplishing the indicated purposes, wherein a simple and effective operating means or mechanism is provided for extending 25 and retracting relatively movable parts of the device.

These and other objects are attained by the means described herein and disclosed in the accompanying drawings, in which:

30 Fig. 1 is an end elevation showing diagrammatically the relationship of parts of a device embodying the invention, the relatively movable bed members being slightly extended.

Fig. 2 is a fragmental plan view of parts shown 35 in Fig. 1.

Fig. 3 is a view of a modified form of device, showing the parts in substantially the same relationship as in Fig. 1.

Fig. 4 is a view of the same general character of 40 Fig. 2 and showing modifications that may be incorporated in a device embodying the invention.

Fig. 5 is an enlarged sectional view on line 5—5 of Fig. 2.

Fig. 6 is an enlarged sectional view on line 6—6 45 of Fig. 2.

Fig. 7 is an enlarged detail view of one of the parts shown in Fig. 3 and forming a detail of the invention.

Fig. 8 is an enlarged diagrammatic view showing 50 details of the invention.

Fig. 9 is a view, somewhat similar to Fig. 1, and showing a modification of the invention.

Fig. 10 is a perspective view showing parts of 55 the device shown in Fig. 9.

Fig. 11 is a fragmental plan view of parts shown in Fig. 9, the relatively movable bed sections being extended.

Fig. 12 is a fragmental detail view showing a pillow support forming part of the back rest, and 5 all of which form part of the invention.

Fig. 13 is a view showing parts shown in Fig. 12, in a different position.

Fig. 14 is an enlarged sectional view on line 14—14 of Fig. 12.

The device shown in Fig. 1 comprises a stationary frame 20 provided with suitable supporting legs or standards 21. Preferably, the frame 20 is a relatively stationary member. The frame 20 may comprise an ordinary rectangular frame of 15 approximately the width and length necessary to provide a comfortable bed and is provided with a suitable wire fabric 22 for providing the equivalent of an ordinary bed spring. The frame 20 may comprise the lateral members 23 and end 20 members 24, and which members are preferably made of angle iron form. The wire fabric 22 is connected to the members 23 and 24 by suitable springs 25. It is intended that when the stationary frame 20 is being used as a bed, suitable bedding or cushions will be disposed over the spring supporting structure provided intermediate the members 23 and 24.

A movable section 26 is tractionsally supported by mounting suitable casters 127 at the corners 30 thereof. The movable member 26 referred to as the seat portion of the studio couch, is hollow to such extent as will permit the same to be moved back and forth for enclosing and exposing the stationary member 20 of the device. Suitable 35 guide means may be provided, if necessary or desirable, for assuring free and easy relative movement of the parts 20 and 26 for the indicated purpose.

As shown in Fig. 1, a means for effecting relative movement of the parts 20 and 26, comprises the back forming member or rail 27 and end or arm rest forming members or rails 28. The members 27 and 28 are pivotally or hingedly connected together at 29 and each of the members 27 and 28 has a hinged or pivotal mounting upon one or the other of the relatively movable members 20 and 26. As shown, the member 27, which preferably is tubular, is of generally inverted U-shaped form and has the free ends of the arms 30 thereof pivotally connected to the ends 24 of the stationary member 20 as shown at 31. The connection of the back rest or support member 27 is preferably such that the hinged connection will permit sepa- 50

ration of the member 27 from the member 20 whereby to make possible the moving of the bed members to positions independent of one another, thereby permitting use of the two bed forming parts of the device as twin beds. The arm rest member 28 of which one is provided at each side of the device, has a pivotal mounting or connection 32 with the seat member 26 adjacent the forward end thereof. The various pivotal mountings are so positioned, in view of the shapes and lengths of the various parts of the device, that by moving the back rest member 27, shown in Fig. 1, in a counter-clockwise direction, the said portion 26 is moved outwardly or projected laterally beyond the stationary member 20. By reversing the direction of movement of the member 27, the movable seat member 26 is moved back to position enclosing the stationary member 20. The connection at 29 may be effected by means of an angle bracket 129 bolted as at 128 to the arm 30, Fig. 5.

Ordinarily cushions are placed upon the seat member 26 and similar pillows are set on end and rest against the cushions on the member 26 and against the back support 27. In order to provide adequate support for the pillows, intermediate the arms 30 of the back rest 27 as well as beneath the base portion 33 thereof, a strap 34 is provided between the arm members 30. Preferably, the strap member comprises two sections, one each of which is attached to one of the arms 30, and the centermost portions of such straps are connected by a spring 35. The spring 35 is sufficiently tensioned to withstand the normal pressure directed upon the straps and the spring incident to persons seated upon the member 26, leaning against the pillows standing on end and supported by the back rest members. The strap members 34 are so connected to the arm members 30 that when the back rest is moved to horizontal position, as shown in Fig. 2, the straps 34 will lie immediately over or upon the stationary frame 20, thus serving to provide a support for the back rest member 27.

The means provided for detachable connection of the back rest member 27 to the stationary member 20 may be varied as desired. As shown in Fig. 2, such means comprises hinge pin 31 carried by an arm such as 30 and having its inner end received in a suitable opening or slot 36 provided either in the frame 20 or in one of the support legs 21 thereof. If the slot or opening 26 is provided in the stationary member 20, such opening may be sufficiently high to permit the back rest to assume the position shown in Fig. 2 incident to the normal turning down action thereof. In instances, however, where it might be desired to have the hinge connection 31 provided between the back rest 27 and a leg such as 21, it is desirable to elongate the slot or opening as shown at 37 so that the hinge pin 31 may be elevated incident to the turning down movement of the member 27 and whereby the frame 27 may assume a substantially horizontal position with the straps 34 in substantially the position shown in Fig. 2. In the horizontal position of the frame 27, it may rest upon suitable blocks or stops such as 51, secured to member 23, Fig. 2.

In the arrangement shown in Fig. 4, the back rest 48 which to all purposes and intents functions as does the back rest 27, carries the wire fabric 41 as distinguished from having such fabric carried by the stationary member 42 and which stationary frame member 42 otherwise corre-

sponds with the stationary member 20 shown in Fig. 1. In this form of device the stationary frame member 42 may be in the nature of a hollow box in which suitable bedding may be stored and the wire fabric 41 carried by the back rest 40 serves as a closure for the open top of the box formed in and by means of the stationary member 42. Similar reference characters are applied to those parts of Fig. 4 that correspond to similarly marked parts of Figs. 1 and 2.

Where the wire fabric 41 is carried by the back member 40, it is desirable to provide a lateral member 43 between the free ends of the arms 44 thereof, whereby to provide suitable anchorage means for the springs 25 and the wire fabric 41. Also, in this form of device, it may be desirable to so arrange the pivot 31 that the back rest 41 assumes a position upon or is supported by the stationary member 42 as distinguished from the arrangement shown in Fig. 2 wherein the back rest 27 clears the stationary member 20.

In Fig. 3 there is provided a stationary frame 300 corresponding to the stationary frame member 20 of Fig. 1, and a back member or support 37 corresponding to member 27 shown in Fig. 1. In lieu of a tubular arm rest such as is shown at 28 in Fig. 1 there is provided a closed arm rail or end member 38 which is secured to and forms part of the bed forming portion of the movable section of the device and corresponding to that part of Fig. 1 indicated as 26. The end members 38 are in the nature of a headboard and a footboard when the device is being used as a bed, and at other times they serve as arm supports. The device shown in Fig. 3 is provided with a linked connection which functions as does the arm rest 28 of Fig. 1. The indicated link connection comprises an inverted L-shaped link 310 having a pivotal mounting at 320 upon the back rest 37 and having a sliding pivotal mounting 340 upon a slotted bracket 350 carried by the end or arm member 38. A similar link and bracket arrangement 310 and 350 is provided at each end of the device. The member 350 is preferably in the form of an angle iron having one of its legs attached to the member 38 and the other end extending at right angle and having formed therein a suitable elongated slot 360 in which the hinge pin 340 may slidably engage. The arrangement of parts is such that as the back member 37 is moved in counter-clockwise direction (see Fig. 3), the link 310 so cooperates, by reason of its pivotal and sliding connections to the member 37 and the bracket 350, that substantially the same relative movement is effected between the stationary frame 30 and the movable seat portion 36, as is attained by corresponding parts shown in Fig. 1. If desired, a suitable upright 39, which may be ornamental as well as utilitarian, may be provided for supporting the upper portion of the bracket 350 and for substantially enclosing and concealing the various operating parts disposed between it and the back member 37. It is to be understood that in the form of device shown in Fig. 3, the stationary member may either carry the wire fabric as does the frame 20 shown in Fig. 2 or the member 300 may be of the hollow box variety shown in Fig. 4 and the wire fabric may be carried by the back member 37.

Figs. 9 to 11 inclusive show generally a structure of the general character shown in Fig. 3 in that the movable member is provided with relatively stationary arm rest members but wherein a means other than that shown in Fig. 3 is employed for

effecting relative movement of the movable and stationary seat and bed forming members. In the form of device shown in Fig. 9, there is used generally the link arrangement shown in Fig. 1, suitable changes being made in the proportioning and attachment of parts whereby to attain substantially the same results.

In Fig. 9 the stationary frame is shown at 99 and the movable seat portion is at 96. The arm rest portion is shown at 98 and the back rest is shown at 91. A link 91 has pivotal mounting at 92 upon the back support 97 and has its other end pivotally connected at 93 to the member 96 whereby upon turning down the member 97, the tractionally supported member 96 is projected in the same manner as similar members are projected in the other forms of the invention. The end or arm rest member 98 may be provided with a suitable opening or slot 94 into which the lower end of the link 91 extends. It is to be understood that the stationary member 99 may be of the form shown in either of Figs. 2 or 4 and that the wire fabric may either be attached to the stationary member 99 or to the movable back support member 97, suitable modification being made to accommodate either of those forms.

In Figs. 12 and 13 there is shown the back member such as 27 in association with a movable pillow supporting member 27 which performs substantially the same function as is performed by the straps 34 and spring 35 shown in Fig. 2. In order that the pillow supporting member 270 may be moved out of possible contact with a stationary member such as 20, the member 270 may be hinged at its opposite ends to the arms 30 of the member 27 so that by reason of such pivotal connection and the crank formation indicated generally at 271, the member 270 may assume the position shown in Fig. 13, and thus obviate interference thereof with any of the stationary members with which the structure might be employed. A suitable stop member 272 may be provided for retaining the member 270 in position against the pressure of the weight of any person resting against any of the pillows standing on edge and supported by the back member 27 and the member 270.

Ordinarily, a large cushion would be placed upon the movable member 26 and a number of pillows would be standing on edge and resting against the member 27 as previously explained. If a device is to be used as a double bed, the pillows standing on edge would be removed and the back member 27 would be moved to horizontal position, thus projecting the movable member to a position at one side of the stationary member. The removed cushion would then be placed over the stationary member 20 and serve as a mattress upon which suitable bedding would then be arranged. If it should be desired to use the device as a set of twin beds, the arms 30 of the back member 27 may be sprung apart sufficiently to permit withdrawal of the hinge pins 31 from the sockets or slots 36 and 37 whereupon the movable portion of the device may be moved to any desired portion of a room without disturbing the stationary portion 20 of the device. In order to return the parts to normal or closed position, the foregoing procedure is reversed.

In those forms of the invention embodying the attachment of the wire fabric to the back rest member, the back rest is preferably not detachable from the stationary member 42, and a detachable hinged connection is provided between the arm rest members 28 and the back rest mem-

ber 40. This may be readily accomplished either at the place of connection of the arm rests upon the back rest; viz., at 440, or at 450, where the arm rest is pivotally connected to the movable member 40. Such detachable connections may be similar to that shown at 31-36, or any other suitable arrangement may be employed. Any equivalent arrangement of parts that will permit telescoping of the members 20 and 26 may be used.

The link 310 provides a simple arrangement for a detachable connection of the character referred to in the preceding paragraph. The link 310 is provided with a slot or pocket 324 adapted to receive a pin 321 carried by back rest 37. A latch 322, carried by link 310 has a pocket 323 adapted to also receive pin 321 and thus pivotally lock the link and back rest together. The particular form of link 310, shown herein, is designed to avoid contact of the back rest member upon the cushion on the movable member, incident to turning down the back rest member for extending the device.

In some forms of the invention, it may be desired to provide a box and wire fabric arrangement as disclosed in Fig. 4, and wherein the wire fabric is separate from the back rest member 40. Under such circumstances, a separate frame for the wire fabric may be hingedly carried by the box formed by the stationary member 42. The form of pillow support shown at 270 is preferably used whereby to permit ready access to the interior of the box without necessarily detaching the tractionally supported member or the back rest member.

The offset structure of the straps 34, shown in Fig. 6, is provided essentially to permit the back rest member to assume a horizontal position in the extended condition of the relatively movable bed members or portions.

What is claimed is:

1. In a device of the class described, the combination of a stationary frame, a spring structure on the frame providing a bed, a back rest member having a transverse rail and extending legs hinged to the frame at the ends of the frame and adjacent one side thereof, a movable member adapted for use as a bed and as a seat or couch member, the movable member being open at one side and hollow to an extent sufficient for it to telescope the stationary member, link means connecting the opposite ends of the movable member with the legs of the back rest, and a U-shaped support carried by the back rest for cooperation with the back rest for supporting a pillow resting on edge on the movable member when the movable member is telescoped over the stationary frame said support including a part spanning the back rest member, and opposed off-set ends pivoted upon the back rest legs for guiding the spanning part from a position closely along and in substantial parallelism with the transverse back rest rail, to a position relatively distant from said rail.

2. In a convertible couch, the combination of a stationary frame having opposite ends and front and rear sides, a movable extendible frame adapted for use as a bed and as a seat, the movable frame being open at one side and hollow to an extent sufficient for it to telescope the stationary frame, a back rest in the form of a U-piece having a transverse upper rail and a leg extending from each end of the rail, said legs each having a free end, means pivoting the free ends of the legs to the stationary frame adjacent to the

5 rear side thereof, for guiding the rail of the back rest to a position along the front of the stationary frame in the extended position of the movable frame, and a crank-shaped pillow support having a back rest span and opposite ends eccentrically related thereto, the ends being pivoted to the legs of the back rest and spaced from the back rest rail, for rotation of the pillow support span from a position closely along the back 10 rest rail to a position relatively distant from said rail.

15 3. In a convertible couch, the combination of a stationary frame having opposite ends and front and rear sides, a movable extendible frame 20 adapted for use as a bed and as a seat, the movable frame being open at one side and hollow to an extent sufficient for it to telescope the stationary frame, a back rest in the form of a U-piece having a transverse upper rail and a leg 25 extending from each end of the rail, said legs each having a free end, means pivoting the free ends of the legs to the stationary frame adjacent to the rear side thereof, for guiding the rail of the back rest to a position along the front of the 30 stationary frame in the extended position of the movable frame, link means connecting the back rest to the movable frame for automatically extending said frame forwardly of the stationary frame upon rotation of the back rest about its 35 pivot means to the said position along the front of the stationary frame, and a crank-shaped pillow support having a back rest span and opposite ends eccentrically related thereto, the ends being pivoted to the legs of the back rest and spaced from the back rest rail, for rotation of the pillow support span from a position closely along the back rest rail to a position relatively distant from said rail.

40 4. In a couch, the combination of a stationary frame having opposite ends and front and rear sides, a back rest in the form of a U-piece having a transverse upper rail and a leg extending from

5 each end of the rail, said legs each having a free end, means pivoting the free ends of the legs to the stationary frame at opposite ends thereof to guide the rail of the back rest toward and from a position in substantial spaced parallelism with and alongside of the front side of the stationary frame, a support carried by the back rest for supporting a pillow, said support including a part spanning the back rest, and off-set ends eccentrically related to the spanning part, and means 10 pivoting said off-set ends to the legs of the U-piece at a location spaced from the rail a distance corresponding to the amount of the off-set of said ends, rotation of the pillow support about its pivots thereby serving to dispose the spanning part selectively closely along the transverse rail, or at a position relatively distant therefrom. 15

5. In a couch, the combination of a stationary frame having opposite ends and a front and rear sides, a back rest in the form of a U-piece having 20 a transverse upper rail and a leg extending from each end of the rail, said legs each having a free end, means pivoting the free ends of the legs to the stationary frame at opposite ends thereof to guide the rail of the back rest toward and from a 25 position in substantial parallelism with and alongside of the front side of the stationary frame, a support carried by the back rest for supporting a pillow, said support including a part spanning the back rest, and off-set ends eccentrically related to the spanning part, and means 30 pivoting said off-set ends to the legs of the U-piece at a location spaced from the rail a distance corresponding to the amount of the off-set of said ends, rotation of the pillow support about 35 its pivots thereby serving to dispose the spanning part selectively closely along the transverse rail, or at a position relatively distant therefrom, and a stop on the back rest for limiting the rotation of the support in one direction about its 40 off-set pivoted ends.

HERBERT A. WUEST.
